US00D949390S

(12) **United States Design Patent** (10) Patent No.: **US D949,390 S**
Wersland et al. (45) Date of Patent: **** Apr. 19, 2022**

- (54) **PERCUSSIVE MASSAGE DEVICE**
- (71) Applicant: **Theragun, Inc.**, Beverly Hills, CA (US)
- (72) Inventors: **Jason Wersland**, Manhattan Beach, CA (US); **Benjamin Nazarian**, Beverly Hills, CA (US); **Jaime Sanchez Solana**, Los Angeles, CA (US); **Eduardo Merino**, Beverly Hills, CA (US); **Trent Hernandez**, Los Angeles, CA (US)
- (73) Assignee: **THERABODY, INC.**, Beverly Hills, CA (US)

(**) Term: **15 Years**

(21) Appl. No.: **29/728,608**

(22) Filed: **Mar. 19, 2020**

(57) **CLAIM**

The ornamental design for a percussive massage device, as shown and described.

DESCRIPTION

FIG. 1 is a top perspective view of a percussive massage device, showing our new design;
FIG. 2 is a right side elevational view, the left side elevational view being a mirror image thereof;
FIG. 3 is a front elevational view thereof;
FIG. 4 is a rear elevational view thereof;
FIG. 5 is a top plan view thereof;
FIG. 6 is a bottom plan view thereof; and,
FIG. 7 is a bottom perspective view.

1 Claim, 5 Drawing Sheets
